(57) **CLAIM**

I claim the ornamental design for an infuser, as shown and described.

DESCRIPTION

FIG. 1 is a perspective view of a first embodiment of an infuser, the infuser having a filter in an unsubmerged configuration;

FIG. 2 is a left side elevational view thereof;

FIG. 3 is a right side elevational view thereof;

FIG. 4 is a front elevational view thereof;

FIG. 5 is a rear elevational view thereof;

FIG. 6 is a top plan view thereof;

FIG. 7 is a bottom plan view thereof; and

FIG. 8 is a perspective view of the infuser, the infuser having the filter in a submerged configuration.

FIG. 9 is a perspective view of a second embodiment of the infuser, the infuser having a filter in an unsubmerged configuration;

FIG. 10 is a left side elevational view thereof;

FIG. 11 is a right side elevational view thereof;

FIG. 12 is a front elevational view thereof;

FIG. 13 is a rear elevational view thereof;

FIG. 14 is a top plan view thereof;

FIG. 15 is a bottom plan view thereof; and

FIG. 16 is a perspective view thereof, the infuser having the filter in a submerged configuration.

The broken lines in the drawing depict portions of the infuser that form no part of the claimed design.

1 Claim, 16 Drawing Sheets
